CLAIM

The ornamental design for a dog booster seat as shown and described.

DESCRIPTION

FIG. 1 is a perspective view of a dog booster seat showing the claimed design;
FIG. 2 is another perspective view thereof;
FIG. 3 is a front elevational view thereof;
FIG. 4 is a rear elevational view thereof;
FIG. 5 is a left side view thereof;
FIG. 6 is a right side view thereof;
FIG. 7 is a top plan view thereof;
FIG. 8 is a bottom plan view thereof; and,
FIG. 9 is an enlarged view of area 9 shown in FIG. 8.
The dashed broken lines illustrate portions of the dog booster seat that form no part of the claimed design, and the dash-dot dashed broken lines define the bounds of enlarged views and form no part of the claimed design.

1 Claim, 9 Drawing Sheets
